HAIR CURLER

Joseph Jacobs, Bridgeport, Conn., assignor to
 The Hayes Donahue Manufacturing Co., Inc.,
 Milford, Conn., a corporation of Connecticut

Application September 16, 1937, Serial No. 164,114

10 Claims. (Cl. 132—33)

This invention relates to improvements in hair waving appliances and has particular reference to a curler of the type in which a hair pin is activated by the operation of a curler to clamp 5 a strand of hair and remain in its clamping position thereon after the curler has been removed.

An object of the invention is to provide an improved curler of the type referred to, which is of simple, practical and economical construction 10 and wherein two hair pin-supporting members cooperate to adjust the pin from a non-clamping to a clamping position with respect to a strand of hair wound upon the mandrel of the curler.

The above and other objects will appear more 15 clearly from the following detailed description when taken in connection with the accompanying drawing which illustrates a preferred embodiment of the inventive idea.

In the drawing:—

20 Figure 1 is an elevation, partly in longitudinal section, of a hair curler constructed in accordance with the invention and showing the parts in position prior to the application of a hair pin to a strand of hair wound upon the curler.

25 Figure 2 is a view similar to Figure 1 showing the elements of the curler in operated position and with the hair pin applied to the strand.

Figure 3 is a fragmentary horizontal section 30 through the curler taken substantially on the line 3—3 of Figure 5.

Figures 4 and 5 are transverse sections on the lines 4—4 and 5—5, respectively, of Figure 1, and

35 Figure 6 is a similar view on the line 6—6 of Figure 2.

Referring more particularly to the drawing, the curler is shown as comprising a tubular mandrel 7 which may be made of any light material. At one end of the mandrel the same is provided 40 with opposed slots 8 forming an opening into which an end of a strand of hair may be inserted preparatory to winding said strand upon the mandrel as indicated in Figure 1.

In accordance with the present invention, 45 means are provided for receiving and supporting a hair pin 9, such as the well known "bobby pin", on the mandrel preliminary to winding the strand of hair thereon and after this winding operation has been completed, said means are operable to adjust the hair pin 9 from a non-clamping to a clamping position relative to the strand of hair. As shown, said means comprises two co-operating members 10 and 11 each of which is substantially 50 in the form of a collar through which the mandrel passes and both of which combine to support

the hair pin 9 in its non-clamping or normal position on the mandrel. When the members 10 and 11 are operated to adjust the hair pin to its clamping or operative position with respect to the strand of hair, the member 10, as will be seen from the following description, has imparted thereto by the member 11 coordinate longitudinal and rotary movements relative to the mandrel, while the member 11 has only a longitudinal movement the initial and major portion of which is made relative to the member 10. During said initial movement of the member 11, the pin 9 is projected from its normal position along the mandrel and toward the strand of hair, and during this movement the member 10 operates to spread the shanks of the pin so that they will extend along the inner and outer convolutions of the curled strand. After the pin has been thus adjusted by the longitudinal movement of the member 11 relative to the member 10 and the 20 pin has almost reached its clamping position, the member 10 is engaged by the member 11 and further movement of the latter to its extreme operated position also imparts a longitudinal movement to the member 10. Simultaneously, the 25 latter member is also rotated and this rotation is designed for the purpose of releasing the hair pin 9 from the member 10 to permit the spread or outer shank of the hair pin to assume its normal position in which it will co-operate with its other shank to clamp the strand of hair therebetween. When this has been accomplished, the members 10 and 11 are restored to their normal 30 positions and the strand of hair with the pin thereon is removed from the mandrel.

The member 10 partially embraces the mandrel 7 and is provided with a beveled peripheral portion 12 the purpose of which will presently appear. Said member is cut to provide an opening 13 which, in the normal position of the member, is out of alignment with the pin 9, but when said member is rotated said opening 13 is brought into alignment with the pin so that the closed end of the latter may be projected through the member at the termination of the longitudinal movement thereof and thus permit the bight of the pin to engage the adjacent edge of the strand of hair. In order that the described rotary movement may be imparted to the member 10 the latter carries a pin 14 which projects into a spiral slot 15 formed in the mandrel. When the member 10 has been actuated to the position of Figure 2 in which the opening 13 has been brought into alignment with the pin 9 means are provided for restoring the member 10 to its normal position of Figure 1 55

after pressure against the member is relieved by the operator releasing the grip upon the member 11. This means is in the form of a spring 16 coiled about a rod 17 extending longitudinally 5 of the interior of the mandrel, with one end of the spring secured to the mandrel and the other abutting against the pin 14. The movement of the member 10 toward the strand of hair compresses said spring and when pressure against 10 said member is relieved the spring 16 acts to restore said member 10 to its normal position.

The member 11 completely encircles the mandrel 7 and is provided with a pin 18 the inner end of which projects into a groove 19 formed 15 in the mandrel 7 and extending from a point adjacent the left hand end of the mandrel as viewed in Figure 1 to the other extremity thereof. By the engagement of the pin 18 in said groove the member 11 is permitted to slide along 20 the mandrel but is prevented from having a rotary movement with respect thereto. The member 11 is provided with an enlargement 20 having a recess 21 therein adapted to receive the closed end or bight of the pin 9 when the latter 25 is being mounted in position preparatory to its application to the strand of hair. In mounting the pin 9 on the mandrel between the members 10 and 11, the free extremity of one of the shanks of the pin 9 is first inserted into the 30 portion of the groove 19 then encircled by the member 10, and the extremity of the other shank is separated from the first extremity and rests upon the periphery of the member 10. The first or inner shank then engages in the groove 19 and 35 the closed end or bight of said pin extends into the recess 21 of the member 11. With the pin thus supported, the strand of hair is wound upon the outer end of the mandrel and when this winding operation has been completed the operator first grasps the member 11 and moves the 40 same toward the member 10. As said member 11 approaches the member 10 the inner shank of the pin travels along the groove 19 and is thus projected into the curled strand of hair. At the 45 same time the outer shank of the pin passes over the member 10 and as the member 11 nears said member 10 the spread of the outer shank increases so that its passage over the outer surface of the strand of hair will be insured. By 50 providing the member 10 with the beveled portion 12 it will be obvious that the spread imparted to the shank will not be unduly increased as the member 11 approaches the member 10. Until the member 11 comes into contact with the member 55 10 the latter has no movement imparted thereto, but when said engagement is effected, and the operator continues to exert pressure against the member 11, the member 10 will also be moved longitudinally until the pin 14 engages the outer end 60 of the slot 15. During this movement, as previously described, the member 10 is rotated and in so doing the opening 13 is brought into alignment with the pin 9. This occurs as the member 10 reaches the right hand extremity of its movement and when the opening and pin are so aligned the outer shank of said pin is permitted to restore 65 to its normal condition in which it will cooperate with the inner shank to clamp the strand of hair therebetween. At this time the closed end 70 of the pin will have been projected through the opening 13 and into engagement with the adjacent edge of the strand of hair so that the pin will be in its proper clamping position. The operator now withdraws the member 11 to its normal 75 position and when the pressure on the mem-

ber 10 is thus relieved the spring 16 will restore said member to its normal position. The strand of hair with the pin clamped thereon may now be removed from the mandrel by an outward pressure against the closed end of the pin toward the 5 free end of the mandrel.

What is claimed is:

1. In a hair curler, a mandrel upon which a strand of hair is wound, and cooperating members normally spaced along the mandrel and supporting a hair pin relative to said mandrel for application to said strand, one of said members having an initial longitudinal movement relative to the other and both having subsequent unitary movements with respect to said mandrel to transfer said pin from its supported position onto said strand. 10

2. In a hair curler, a mandrel upon which a strand of hair is wound, and cooperating members normally spaced on said mandrel for supporting opposite end portions of a hair pin preliminary to its application to said strand, said members being successively movable relative to said mandrel when applying said pin to said strand and one of said members having means 20 to spread the shanks of said pin during the movement of the other member.

3. In a hair curler, a mandrel upon which a strand of hair is wound, and cooperating members supporting a hair pin preliminary to its application to said strand, one of said members having an initial movement relative to the other when applying said pin to said strand and thereafter actuating the other member to transfer said pin from its supported position onto said strand. 30

4. In a hair curler, a mandrel upon which a strand of hair is wound, and cooperating members supporting a hair pin relative to said mandrel for application to said strand, one of said members having only a longitudinal movement 40 relative to said mandrel and the other member having coordinate longitudinal and rotary movements with respect to the longitudinal axis of said mandrel, said members coacting during the movements thereof to transfer said pin from its supported position onto said strands. 45

5. In a hair curler, a mandrel upon which a strand of hair is wound, normally spaced pin-supporting members mounted for movements on said mandrel, one of said members having a longitudinal movement and the other coordinate longitudinal and rotary movements effected by contact of the first named member with the second member during a portion of the movement of the former, the movements of said members 50 transferring the pin supported thereby onto said strand. 55

6. In a hair curler, a mandrel upon which a strand of hair is wound, a pin-supporting member slideable on said mandrel and having means to spread the shanks of said pin and further having an opening normally out of alignment with said pin when the latter is in its supported position, means to impart rotary movement to said member during its sliding movement so as to align said opening with said pin, and a second pin-supporting member slideable on said mandrel and operable during its sliding movement to propel said pin toward a clamping position relative to said strand, the spreading 60 means of the first named member then acting to further spread said shanks, said second member thereafter contacting said first member to slide the same and thereby cause said second member to also rotate said first member 65 70

75

to render said spreading means ineffective and align said pin with said opening so that the shanks of the pin will clamp said strand.

7. In a hair curler, a mandrel upon which a strand of hair is wound and which is provided with a longitudinal groove for the reception of a shank of a hair pin, said mandrel further having a spiral slot therein, a pin-supporting member slidably mounted on said mandrel and having a pin engaging in said slot, said member being engaged by the other shank of the hair pin in the normal position of said member to maintain the shanks of the pin separated, a second pin-supporting member slidably mounted on said mandrel normally spaced from the first named supporting member, said second member having means to engage the closed end of said hair pin and further having a pin engaged in the groove in said mandrel to prevent turning movement of said member, said second member being initially slidable along said mandrel in the direction of the first named supporting member to force said pin toward a clamping position relative to said strand, and thereafter contacting said first named supporting member to slide the latter and thereby effect its rotation through the medium of said spiral slot so as to disengage the second named shank of said pin from the first named supporting member so that both shanks of the pin will engage and clamp the strand of hair, and a spring acting to restore the first named pin-supporting member to its normal position after the hair pin is in clamping engagement with said strand.

8. In a hair curler, a mandrel upon which a strand of hair is wound, normally spaced pin-supporting members mounted for movements on said mandrel, one of said members being initially movable relative to the other along said mandrel and into engagement with the latter member, and the two members being thereafter movable in unison along the mandrel, said other member having an opening therein normally out

of alignment with a hair pin disposed on said mandrel between said members, and a connection between said mandrel and other member operable to rotate the latter during its unitary movement with the first named member so as to align said opening with said hair pin.

9. In a hair curler, a mandrel upon which a strand of hair is wound, normally spaced collars embracing said mandrel and supporting a hair pin therebetween, one of said collars being movable along said mandrel into engagement with the other collar so as to also propel the latter along the mandrel, said other collar having its periphery engaged by a shank of said pin so as to spread said shank during initial movement of the first named collar relative thereto, and further having an opening normally out of alignment with said pin and through which the latter passes onto the strand of hair, and coating means between said mandrel and said other collar to rotate the latter about the mandrel when it is propelled therealong by the first named collar so as to align said opening with said pin.

10. In a hair curler, a mandrel upon which a strand of hair is wound, normally spaced collars embracing said mandrel and supporting a hair pin therebetween, one of said collars being movable along said mandrel into engagement with the other collar so as to also propel the latter along the mandrel, said other collar having its periphery engaged by a shank of said pin so as to spread said shank during initial movement of the first named collar relative thereto, and further having an opening normally out of alignment with said pin and through which the latter passes onto the strand of hair, and a pin and spiral slot connection between said mandrel and said other collar to effect rotation of the latter about the mandrel as said collar is propelled by the first named collar to thereby align said opening with said pin.

JOSEPH JACOBS.
